FIG. III.

UNITED STATES PATENT OFFICE.

AUGUST FREDERICK KILLIAN, OF PALMYRA, NEW JERSEY.

AUTOMATIC STOCKING-LENGTH-MEASURING DEVICE FOR KNITTING-MACHINES.

1,289,811.

Specification of Letters Patent. Patented Dec. 31, 1918.

Application filed January 13, 1917. Serial No. 142,575.

To all whom it may concern:

Be it known that I, AUGUST FREDERICK KILLIAN, a citizen of the United States, residing at Palmyra, in the State of New Jersey, have invented a certain new and useful Improvement in Automatic Stocking-Length-Measuring Devices for Knitting-Machines, whereof the following is a specification, reference being had to the accompanying drawings.

It is the object of my invention to provide a rotary knitting machine, of the class in which the needle cylinder is rotary, with means to precisely predetermine the actual lengths of the stocking tube between enlargements thereof, for the heel and toe pockets, regardless of the number of courses of loops. Ordinarily, such lengths of the fabric produced by machines of that class are determined solely by the number of courses of loops; so that the actual length varies in accordance with even slight variations in the tension of the thread. For instance, two machines apparently adjusted alike, both as to the number of courses and as to the tension of the thread, may respectively produce stockings differing in length by three inches or more. Consequently, where a number of such machines are employed a great deal of time and labor is necessarily expended in sorting the stockings and matching them in pairs of substantially the same length. My invention has the purpose and effect of dispensing with such waste of time and labor by predetermination of the actual length of each stocking, regardless of the number of courses of loops therein. Although stockings produced in accordance with my invention may vary to a considerable extent in the number of courses of loops in a given length, in accordance with variations in the tension of the threads, such variations are negligible as far as the commercial value of the product is concerned.

As hereinafter described, my invention includes a roller which is engaged and turned by the knit tube as the latter is drawn from the needles; so that said roller is turned in precise accordance with the actual length of the fabric which passes it, and said roller is provided with means connecting it with pattern mechanism, which may be of any suitable construction, whereby the movement of such mechanism to effect the shaping of the knit tube is initi-

ated when said roller reaches a predetermined point in its revolution; the motion of the pattern mechanism thus initiated being automatically terminated by means included in the pattern mechanism independently of said roller.

I am aware that it is not broadly new to provide a knitting machine with pattern mechanism the motion of which is controlled by means movable in accordance with the actual length of the fabric produced, without regard to the number of courses therein. However, so far as I am aware, no such device of the prior art has been designed or adapted for coöperation with a knitting machine wherein the needle cylinder rotates during the knitting operation.

My invention includes the various novel features of construction and arrangement hereinafter more definitely specified.

In the drawings; Figure I is a fragmentary front elevation of an automatic knitting machine of the "Banner" type having a convenient embodiment of my invention applied thereto.

Fig. II is a fragmentary elevation of the mechanism shown in Fig. I, as seen from the right hand side of that figure.

Fig. III is a fragmentary elevation of a smaller portion of said machine, as seen from the left hand side of Fig. I.

Fig. IV is a fragmentary plan sectional view, taken on the line IV, IV in Figs. I to III inclusive.

In said figures; I have shown only so much of the ordinary elements of said automatic knitting machine as are necessary to illustrate the application of my invention thereto, including the rotary needle cylinder 1 provided with needles 2 arranged to be operated by the cam cylinder 3 which is stationary on the machine frame 4. The main shaft 5 has, fast at its inner end, the bevel gear 6 engaging the bevel gear 7 on the lower end of said needle cylinder, as indicated in Fig. I. Said shaft 5 carries on its central enlargement 8 the clutch 9 which turns with said shaft but is keyed to slide thereon, when moved by the lever 12, so that said shaft may be alternately driven by the gears 13 and 14, both of which are normally loose on said shaft. Said gear 13 is fast on the sleeve 16 having on its outer end the usual tight and loose pulleys 17 and 18 and the operating handle 19, and is the main driving gear. As shown in Fig. II, said

main driving gear 13 engages the crank gear 20, on the countershaft 21, and said gear has the radially adjustable crank pin 22 pivotally connected by the link 23 with the stud 24 on the arm 26 of the sectoral gear 27 which is mounted to oscillate on the shaft 28 in said frame 4 and engages with said gear 14 on said main shaft 5.

It is to be understood that the arrangement above described is such that when said shaft 5 is engaged by the clutch 9 with the main driving gear 13, they, and the needle cylinder 1, are continuously rotated, but when said shaft 5 is engaged by said clutch 9 with the gear 14, said shaft 5 and the needle cylinder are merely oscillated, to the extent determined by the radial position of the crank pin 22.

Said machine also includes, as ordinary elements thereof, the pattern shaft 30, shown in Figs. II and IV, on which is loosely mounted the chain ratchet wheel 31, carrying the pattern chain 32. Said pattern wheel 31 is rotated, step by step, by the cam pawl 34 which successively engages the teeth thereof and is carried and oscillated by said oscillatory sectoral gear 27, in definite relation to the movement of the needle cylinder, regardless of whether the latter is being continuously rotated or oscillated, so that said chain 32 is shifted, in the direction of the arrow marked thereon in Fig. II, in definite relation to the movement of said needle cylinder. Said pattern shaft 30, which extends loosely through said chain ratchet wheel 31, is rotated, step by step, one revolution for each complete stocking length, by the pawl 35, which is also carried by said oscillatory sectoral gear 27. Said pawl 35 engages the cam ratchet wheel 37 which is fast on said shaft 30, so as to turn it with each oscillatory movement of said sectoral gear 27; but said pawl 35 is normally upheld in the idle position shown in Fig. II, by the oscillatory pawl holder 38 which is so weighted that it normally hangs in the position shown in Fig. I but has the projection 39 adapted to be encountered by high links 41, which are carried in properly spaced relation in said chain 32, and arranged to raise said pawl holder 38 from the position shown in Fig. I, and thus permit said pawl to engage said cam ratchet wheel 37.

Said machine is so constructed and arranged as to knit a stocking tube of a pattern represented by the total length of said chain 32 and including leg, heel, foot and toe portions; said heel and toe portions being knit by oscillatory movement of said needle cylinder and said leg and foot portions being circularly knit by continuous rotary movement of said needle cylinder. However, as hereinafter described, my invention is applied to said machine to precisely determine the lengths of the circular

knit portions of the stocking tube, without regard to the other portions of said tube, although my invention is arranged to cooperate, in proper time, with the other elements of the machine by which the knitting of all other portions of the stockings is controlled and effected.

As indicated in Fig. I; said rotary needle cylinder 1 carries the tubular can 46, which rotates with said cylinder, and into which the fabric 47 knit by said needles 2 is discharged. Ordinarily, said fabric 47 is drawn directly downward into said can by the pair of feed rollers 48 and 49 having shafts 50 and 51 which are journaled transversely in said can; said rollers being turned step by step by mechanism including the lever 53 which is operated by encountering a cam supported by said frame 4, independently of said can 46. However, in accordance with my invention, I interpose the measuring roller 55, in said can 46, between said needles 2 and said pair of feed rollers 48 and 49 so that said roller 55 is arranged to be engaged and turned by said fabric 47, in the direction of the arrow marked thereon in Fig. I. Said roller 55 has the shaft 56 journaled transversely in said can 46 and has the driving gear 57, exterior to said can, engaging the pattern gear wheel 58, which is journaled on the exterior of said can and has a circular series of sockets, parallel with its axis, in which pattern studs 61, 62, 63, 64 and 65 are changeably fitted. The tappet cam lever 67, is fulcrumed at 68 on said can 46 and arranged to be operated by said studs 61 to 65 inclusive, as said pattern wheel 58 is turned, in the direction of the arrow marked thereon in Fig. I, in accordance with the progress of said fabric 47 downward in said can 46.

Said tappet lever 67 and mechanism connected therewith as above described, carried by and rotated with said can 46 are arranged to operate the lever 70 which has a ring end encircling said can 46 as shown in Fig. IV, but is supported independently of said can, upon the rock shaft 71 which is journaled in said frame 4 and in the bracket 72 as shown in Figs. III and IV. Said rock shaft 71 carries the lever arm 74, which is in rigid relation therewith and connected by the spring 75 with the frame 4, as indicated in Fig. II, so that said lever 70 is normally resiliently held with its ring end bearing upon said tappet lever 67 as shown in Figs. I and III. Said lever arm 74 is pivotally connected with the link 76 which is pivotally connected to the pawl lever 77 which is mounted to oscillate loosely on the ratchet shaft 79 and provided with the spring pressed pawl 80 adapted to engage a single notch 81 in the ratchet disk 82 which is rigidly connected with said shaft 79. Said shaft 79 is mounted to rotate in the bearing 130

brackets 84 and 85 which are rigidly connected with said frame 4 as indicated in Figs. II, III and IV. Said shaft 79 also has rigidly connected therewith the cam disk 86, indicated in Figs. II and IV, which has the single notch 87 to receive the cam projection 88 of the pawl tripping lever 89 which is fulcrumed at 90 on said frame 4 as indicated in Figs. II and IV, and, when engaged with said pawl disk 86 as indicated in Fig. II, under pressure of the spring 91 which connects said lever 89 with the pin 92 on the frame 4, said lever 89 upholds said pawl 34 in idle position, so that it does not operate said chain ratchet wheel 31. Said lever 89 is tripped to lower said pawl 34 into operative relation with said ratchet wheel 31, by rotation of said shaft 79, and said pawl 34 continues to operate said chain ratchet wheel 31, step by step, with each oscillation of said sectoral gear 27, until said notch 87 is again presented beneath the cam projection 88 on said lever 89, when said lever 89 being drawn down by said spring 91 again uplifts said pawl 34 into the idle position shown in Fig. II.

The mechanism for effecting such intermittent motion includes the ratchet wheel 94, which is rigidly connected with said shaft 79. As shown in Fig. II, said ratchet wheel 94 is spaced for twenty-six teeth, but has only twenty-four teeth, two of the teeth being omitted to form the blank space 95 which is normally presented in the position shown in Fig. II; so that the pawl 96 then reciprocates idly at said blank space. Said pawl 96 is carried by the pawl lever 97 which is mounted to oscillate loosely on said shaft 79 and connected by the link 98 with the rock arm 99 on said shaft 28, which is in rigid relation with said sectoral gear 27, so that the oscillatory movement of the latter is imparted to said pawl lever 97. However, the oscillatory movement thus imparted to the pawl 96, is not effective to turn the ratchet wheel 94 until the latter has been turned in the direction of the arrow marked thereon in Fig. II, to a sufficient extent to present one of its teeth in engagement with said pawl 96. Such preliminary movement is effected by the pawl 80 engaging the pawl disk 82 at the opposite end of said shaft 79, when said ring lever 70 is uplifted by the tappet lever 67, when the latter is uplifted by one of the pattern studs, 61 to 65 inclusive, carried by said pattern gear wheel 58. Said ratchet wheel 94 is conveniently provided with the keeper pawl 100 which is pressed into engagement therewith by the spring 101, as shown in Fig. II, to prevent accidental displacement of said ratchet wheel.

Therefore, it is to be understood that the movement of the ordinary pattern mechanism, including said chain wheel 31, is

initiated when said roller 55 reaches a pre-determined point in its revolution, by one of the pattern studs 61 to 65 inclusive then uplifting the tappet lever 67 and ring lever 70 so as to turn said shaft 79, trip the lever 70 89 and thus lower the pawl 34 into operative relation with said chain ratchet wheel 31; and that the motion of the pattern mechanism thus initiated is automatically terminated upon the completion of a single 75 revolution of said shaft 79, by said tripping lever 89 being again shifted by said spring 91, into the position shown in Fig. II, thus uplifting said pawl 34 from said chain wheel 31 and thus causing it to operate idly thereafter until the operation of my improved mechanism is repeated.

In the form shown, the stud 61 is at the starting point of a stocking blank, the machine being set to "loop around" to form 85 a zone at which the tube is severed. The stud 62 corresponds with the point where the machine begins to knit with cotton thread to form the upper end of the "garter top." The stud 63 initiates the knitting 90 of mercerized thread, in continuation of the "garter top." The stud 64 initiates the knitting of the "boot", with silk thread, and the stud 65 initiates the knitting of the "high 95 splice" and heel.

Of course, said pattern wheel 58 remains stationary during the knitting of each heel and toe pocket, because the fabric is not then progressed by said feed rollers 48 and 49, and, in order to prevent interference of 100 my special pattern mechanism with the ordinary pattern mechanism, during such oscillatory knitting: I find it convenient to provide the auxiliary tripping lever 104 for said pawl 96. As indicated in Figs. II and IV, said lever 104 is fulcrumed at 105 in connection with the frame 4, is provided with the spring 106 connected with said frame 4, and has the cam projection 107 adapted to encounter the cams 108 and 109 105 on the cam disk 110 which is rigidly connected with said pattern shaft 30 and therefore turned by said pawl 35 engaging said ratchet wheel 37; so that said lever 104 may be tilted at predetermined intervals in the rotation of said pattern shaft 30. The opposite end of said lever 104 is formed as a cam 111 adapted to encounter the pin 112 on said pawl 96 and thus uplift the latter and render it idle, at the intervals predetermined by the location of said cams 108 and 109. Said cam 108 shifts said tripping lever 104 preliminary to the knitting of each heel pocket and said cam 109 shifts said lever preliminary to the knitting of each 110 toe pocket.

Said cam disk 110 is part of the ordinary pattern mechanism of the machine illustrated, adapted to coöperate with levers tilted by the cams 114 and 115 indicated in 130

Fig. II. However, the specific construction and arrangement of that portion of the pattern mechanism has nothing to do with my present invention and I have omitted said 5 levers.

As far as I am aware, it is broadly new to provide a knitting machine, of the type in which the needle cylinder rotates, with a measuring roller which is engaged and 10 turned by the knit tube as the latter is drawn from the needles, and which is provided with means connecting it with pattern mechanism whereby the movement of such mechanism is controlled in definite relation to the 15 actual length of the fabric knit, regardless of the number of courses therein. Therefore, I do not desire to limit myself to the precise details of construction and arrangement herein set forth, as it is obvious that 20 various modifications may be made therein without departing from the essential features of my invention as defined in the appended claims.

I claim:

25 1. In an automatic circular knitting machine, the combination with a rotary needle cylinder provided with needles; of a stationary cam cylinder arranged to operate said needles; a tubular can carried by and 30 rotated with said needle cylinder, through which the fabric knit by said machine is discharged; a pair of feed rollers having shafts journaled transversely in said can, arranged to draw said fabric; a measuring 35 roller arranged to engage and be turned by said fabric, having a shaft journaled transversely in said can, between said needle cylinder and said feed rollers; a driving gear on said measuring roller shaft, exterior to 40 said can; a pattern gear wheel journaled on the exterior of said can, driven by said driving gear, and having a circular series of sockets parallel with its axis; pattern studs changeably fitted in said sockets; a tappet 45 cam lever fulcrumed on said can, arranged to be operated by said studs as said pattern wheel is turned; a lever fulcrumed independently of said can, having a ring end encircling said can, and arranged to be oper- 50 ated by said tappet lever; means operatively connecting said ring lever to control the knitting operation of said machine, including a ratchet shaft, a pawl lever mounted to oscillate loosely on said shaft and carrying 55 a pawl, a ratchet disk fixed on said shaft in position to engage said pawl, a ratchet wheel fixed on said shaft, and having a blank space on its tooth face, another pawl lever mounted to oscillate loosely on said shaft and carrying a pawl in position to engage 60 said ratchet wheel; an oscillatory shaft; a rock arm rigid on said oscillatory shaft; a link operatively connecting said rock arm with said last named pawl lever; a cam disk on 65 said ratchet shaft; a tripping lever arranged to coöperate with said cam disk; a sectoral gear on said oscillatory shaft; a pawl carried by said sectoral gear; a chain ratchet wheel adapted to be operated by the last named pawl when released by said tripping lever; and a pattern chain arranged to be progressed by said chain ratchet wheel to control the knitting operation of said machine.

to coöperate with said cam disk; a sectoral gear on said oscillatory shaft; a pawl carried by said sectoral gear; a chain ratchet wheel adapted to be operated by the last named pawl when released by said tripping lever; 70 a pattern chain arranged to be progressed by said chain ratchet wheel to control the knitting operation of said machine; a pattern shaft extending loosely through said chain wheels; means arranged to turn said pattern 75 shaft one revolution for each complete stocking cycle of operation of said machine; heel and toe cams carried by said pattern shaft; and an auxiliary tripping lever arranged to be operated by said heel and toe cams to 80 render said pawl which actuates said ratchet wheel idle during the operation of knitting each heel and toe pocket.

2. In a circular knitting machine, the combination with a rotary needle cylinder 85 provided with needles; of a stationary cam cylinder arranged to operate said needles; a tube carried by and rotated with said needle cylinder, through which the fabric knit by said machine is discharged; a pair of feed 90 rollers arranged to draw said fabric; a measuring roller arranged to engage and be turned by said fabric, having a shaft journaled in said tube, between said needle cylinder and said feed rollers; a driving gear on 95 said measuring roller shaft; a pattern gear wheel journaled on said tube, driven by said driving gear, and having a circular series of sockets; pattern studs changeably fitted in said sockets; a tappet cam lever fulcrumed on said tube, arranged to be operated by said 100 studs as said pattern wheel is turned; a lever fulcrumed independently of said tube, having a ring end encircling said tube, and arranged to be operated by said tappet lever; means 105 operatively connecting said ring lever to control the knitting operation of said machine, including a ratchet shaft, a pawl lever mounted to oscillate loosely on said shaft and carrying a pawl, a ratchet disk fixed on said 110 shaft in position to engage said pawl, a ratchet wheel fixed on said shaft, and having a blank space on its tooth face, another pawl lever mounted to oscillate loosely on said shaft and carrying a pawl in position to engage 115 said ratchet wheel; an oscillatory shaft; a rock arm rigid on said oscillatory shaft; a link operatively connecting said rock arm with said last named pawl lever; a cam disk on 120 said ratchet shaft; a tripping lever arranged to coöperate with said cam disk; a sectoral gear on said oscillatory shaft; a pawl carried by said sectoral gear; a chain ratchet wheel adapted to be operated by the last named pawl when released by said tripping 125 lever; and a pattern chain arranged to be progressed by said chain ratchet wheel to control the knitting operation of said machine.

3. In a circular knitting machine, the combination with a rotary needle cylinder pro- 130

- vided with needles; of a stationary cam cylinder arranged to operate said needles; a tube carried by and rotated with said needle cylinder, through which the fabric knit by 5 said machine is discharged; a measuring roller arranged to engage and be turned by said fabric, having a shaft journaled in said tube; a driving gear on said measuring roller shaft; a pattern gear wheel journaled 10 on said tube, driven by said driving gear, and having a circular series of sockets; pattern studs changeably fitted in said sockets; a lever arranged to be operated by said studs as said pattern wheel is turned; means operatively 15 connecting said lever to control the knitting operation of said machine, including a ratchet shaft, a pawl lever mounted to oscillate loosely on said shaft and carrying a pawl, a ratchet disk fixed on said shaft 20 in position to engage said pawl, a ratchet wheel fixed on said shaft, and having a blank space on its tooth face, another pawl lever mounted to oscillate loosely on said shaft and carrying a pawl in position to engage 25 said ratchet wheel; an oscillatory shaft; a rock arm rigid on said oscillatory shaft; a link operatively connecting said rock arm with said last named pawl lever; a cam disk on said ratchet shaft; a tripping 30 lever arranged to coöperate with said cam disk; a sectoral gear on said oscillatory shaft; a pawl carried by said sectoral gear; a chain ratchet wheel adapted to be operated by the last named pawl when released 35 by said tripping lever; and a pattern chain arranged to be progressed by said chain ratchet wheel to control the knitting operation of said machine.
4. In an automatic fabric length measuring device for a knitting machine, the combination with needles and cams arranged to operate said needles; of a rotary tube through which the fabric knit by said machine is discharged; means arranged to rotate 40 said tube during the knitting operation; a pair of feed rollers having shafts journaled transversely in said tube, arranged to draw said fabric; a measuring roller arranged to engage and be turned by said fabric, having a shaft journaled transversely in said tube, 45 between said needles and said feed rollers; a driving gear on said measuring roller shaft, exterior to said tube; a pattern gear wheel journaled exterior to, but carried by, said tube, driven by said driving gear, and having a circular series of sockets parallel with its axis; pattern studs changeably fitted in said sockets; and pattern mechanism, including a lever in coöoperative relation with 50 said studs, whereby the knitting operation of said machine is controlled, in accordance with the actual length of said fabric, regardless of the number of courses of loops therein.
5. In an automatic fabric length measuring device for a knitting machine, the combination with needles and cams arranged to operate said needles; of a rotary tube through which the fabric knit by said machine is discharged; means arranged to rotate 55 said tube during the knitting operation; a pair of feed rollers having shafts journaled transversely in said tube, arranged to draw said fabric; a measuring roller arranged to engage and be turned by said fabric, having a shaft journaled transversely in said tube, between said needles and said feed rollers; a driving gear on said measuring roller shaft, exterior to said tube; a pattern gear wheel journaled exterior to, but carried by, 60 said tube, driven by said driving gear, and having a circular series of sockets parallel with its axis; pattern studs changeably fitted in said sockets; and pattern mechanism, including a lever in coöoperative relation with said studs, whereby the knitting operation of said machine is controlled, in accordance with the actual length of said fabric, regardless of the number of courses of loops therein.
6. In an automatic fabric length measuring device for a knitting machine, the combination with needles and cams arranged to operate said needles; of a rotary tube through which the fabric knit by said machine is discharged; means arranged to rotate 65 said tube during the knitting operation; a pair of feed rollers having shafts journaled transversely in said tube, arranged to draw said fabric; a measuring roller arranged to engage and be turned by said fabric, having a shaft journaled transversely in said tube, between said needles and said feed rollers; a driving gear on said measuring roller shaft, exterior to said tube; a pattern gear wheel journaled exterior to, but carried by, said tube, driven by said driving gear, and having a circular series of sockets parallel with its axis; pattern studs changeably fitted in said sockets; and pattern mechanism, including a lever in coöoperative relation with 70 said studs, whereby the knitting operation of said machine is controlled, in accordance with the actual length of said fabric, regardless of the number of courses of loops therein.
7. In an automatic fabric length measuring device for a knitting machine, the combination with needles and cams arranged to operate said needles; of a measuring roller arranged to engage and be turned by the fabric knit by said machine, having a shaft; a driving gear on said measuring roller shaft; a pattern gear wheel driven by said driving gear, and having a series of pattern studs; means supporting said pattern gear wheel for rotation, with the needles, upon an axis transverse to its shaft; and pattern mechanism, including a lever in coöoperative relation with said studs, whereby the knitting operation of said machine is controlled, 75 in accordance with the actual length of said fabric, regardless of the number of courses of loops therein.
8. In an automatic fabric length measuring device for a knitting machine, the combination with needles and cams arranged to operate said needles; of a pattern shaft; means arranged to turn said pattern shaft one revolution for each complete stocking cycle of operation of said machine; heel and toe cams carried by said pattern shaft; a pattern chain; a pattern chain ratchet wheel, loose on said pattern shaft and engaging said chain; a pawl arranged to turn said chain ratchet wheel; a tripping lever arranged to render said pawl idle; a ratchet shaft; a cam disk on said ratchet shaft arranged to operate said tripping lever; a ratchet wheel on said ratchet shaft having a blank space; a pawl having means arranged to continuously reciprocate it during the operation of said machine, but normally idle in said blank space; an auxiliary tripping lever arranged to be operated by said heel and toe cams to render said pawl which actuates said ratchet wheel idle during the operation of said machine.

ing the operation of knitting each heel and toe pocket; means arranged to turn said blank space of said ratchet wheel away from said pawl to permit the latter to turn said wheel, including a lever; a pattern gear wheel having studs arranged to actuate the last named lever; a measuring roller arranged to be turned by the fabric knit by said machine; and means operatively connecting said measuring roller with said pattern gear wheel; whereby the knitting operation of said machine is controlled, in accordance with the actual length of said fabric, regardless of the number of courses 15 of loops therein.

8. In an automatic fabric length measuring device for a knitting machine, the combination with needles and cams arranged to operate said needles; of a pattern shaft; 20 means arranged to turn said pattern shaft one revolution for each complete stocking cycle of operation of said machine; heel and toe cams carried by said pattern shaft; a pattern chain; a pattern chain ratchet wheel, 25 engaging said chain; a pawl arranged to turn said chain ratchet wheel; a tripping lever arranged to render said pawl idle; a ratchet shaft; a cam disk on said ratchet shaft arranged to operate said tripping 30 lever; a ratchet wheel on said ratchet shaft having a blank space; a pawl having means arranged to continuously reciprocate it during the operation of said machine, but normally idle in said blank space; an auxiliary 35 tripping lever arranged to be operated by said heel and toe cams to render said pawl which actuates said ratchet wheel idle during the operation of knitting each heel and toe pocket; means arranged to turn said 40 blank space of said ratchet wheel away from said pawl to permit the latter to turn said wheel, including a lever; a pattern gear wheel arranged to actuate the last named lever; a measuring roller arranged to be 45 turned by the fabric knit by said machine; and means operatively connecting said measuring roller with said pattern gear wheel; whereby the knitting operation of said machine is controlled, in accordance 50 with the actual length of said fabric, regardless of the number of courses of loops therein.

9. In an automatic fabric length measuring device for a knitting machine, the combination with needles and cams arranged to operate said needles; of a pattern shaft; means arranged to turn said pattern shaft in accordance with the operation of said machine; a pattern chain; a pattern chain 55 wheel, engaging said chain; a measuring roller arranged to be turned by the fabric knit by said machine; and means operatively connecting said measuring roller with said pattern shaft and with said pattern chain wheel, including a variable pattern 60

gear wheel and means operatively connecting it with said measuring roller, arranged to turn it on an axis transverse to the length of said fabric, and means supporting said pattern gear wheel for rotation, with the 70 needles, upon an axis transverse to its axis of rotation aforesaid; whereby the knitting operation of said machine is controlled, in accordance with the actual length of said fabric, regardless of the number of courses 75 of loops therein.

10. In an automatic circular knitting machine, the combination with a rotary needle cylinder provided with needles; of a stationary cam cylinder arranged to operate 80 said needles; a tubular can carried by and rotated with said needle cylinder, through which the fabric knit by said machine is discharged; a pair of feed rollers having shafts journaled transversely in said can, 85 arranged to draw said fabric; a measuring roller arranged to engage and be turned by said fabric, having a shaft journaled transversely in said can, between said needle cylinder and said feed rollers; a driving gear on said measuring roller shaft, exterior to said can; a pattern gear wheel journaled on the exterior of said can, driven by said driving gear, and having a circular series of sockets parallel with its axis; pattern 90 studs changeably fitted in said sockets; a tappet cam lever fulcrumed on said can, arranged to be operated by said studs as said pattern wheel is turned; a lever fulcrumed independently of said can, having a ring 95 end encircling said can; and means operatively connecting said ring lever to control the knitting operation of said machine.

11. In a circular knitting machine, the combination with a rotary needle cylinder 105 provided with needles; of a stationary cam cylinder arranged to operate said needles; a measuring roller, carried by said needle cylinder, arranged to engage and be turned by the fabric knit by said machine; and means operatively connecting said measuring roller to control the knitting operation of said machine in accordance with the actual length of said fabric, regardless of the number of courses of loops therein, including a variable pattern wheel rotatable upon an axis transverse to the axis of said needle cylinder and carried with said cylinder, and means whereby said pattern wheel has a continuous planetary movement, contemporaneous with and consequent upon the movement of the needle cylinder.

12. In an automatic circular knitting machine, the combination with a rotary needle cylinder provided with needles; of a stationary cam cylinder arranged to operate 110 said needles; a tubular can carried by and rotated with said needle cylinder, through which the fabric knit by said machine is discharged; a measuring roller arranged to 115

engage and be turned by said fabric, having a shaft journaled transversely in said can; a driving gear on said measuring roller shaft, exterior to said can; a pattern gear wheel journaled on the exterior of said can, driven by said driving gear, and having a circular series of sockets parallel with its axis; pattern studs changeably fitted in said sockets; a tappet cam lever fulcrumed on said can, arranged to be operated by said studs as said pattern wheel is turned; a lever fulcrumed independently of said can, having a ring end encircling said can; and means operatively connecting said ring lever to control the knitting operation of said machine.

13. In an automatic circular knitting machine, the combination with a rotary needle cylinder provided with needles; of a stationary cam cylinder arranged to operate said needles; a tubular can carried by and rotated with said needle cylinder, through which the fabric knit by said machine is discharged; a measuring roller arranged to engage and be turned by said fabric, having a shaft journaled transversely in said can; a pattern wheel exterior to said can, driven by said measuring roller; a tappet cam lever fulcrumed on said can, arranged to be operated by said pattern wheel as the latter is turned; a lever fulcrumed independently of said can, having a ring end encircling said can; and means operatively connecting said ring lever to control the knitting operation of said machine.

14. In an automatic circular knitting machine, the combination with a rotary needle cylinder provided with needles; of a sta-

tionary cam cylinder arranged to operate said needles; a measuring roller carried with said rotary needle cylinder and arranged to be turned by the fabric knitted; a pattern wheel, also carried with said needle cylinder, arranged to rotate upon a horizontal axis and having variable projections; a lever fulcrumed on a horizontal axis, independently of said needle cylinder, arranged to be lifted by the projections on said pattern wheel; and means operatively connecting said lever to control the knitting operation of said machine.

15. In an automatic circular knitting machine, the combination with a rotary needle cylinder provided with needles; of a stationary cam cylinder arranged to operate said needles; a tube carried by and rotated with said needle cylinder, through which the fabric knit by said machine is discharged; a measuring roller, carried with said needle cylinder, arranged to engage and be turned by said fabric; a lever fulcrumed independently of said tube, having a ring end encircling said tube; means operatively connecting said measuring roller with said lever, arranged to intermittently operate said lever, in accordance with the length of the fabric knit; and means operatively connecting said ring lever to control the knitting operation of said machine.

In testimony whereof, I have hereunto signed my name at Philadelphia, Pennsylvania, this thirteenth day of December, 1916.

AUGUST FREDERICK KILLIAN.
